UNITED STATES PATENT OFFICE.

WILLIAM B. TURNER, OF WILMINGTON, DELAWARE, ASSIGNOR TO W. B. TURNER
MACHINE COMPANY, A CORPORATION OF WEST VIRGINIA.

LEATHER-FINISHING MACHINE.

1,102,368.

Specification of Letters Patent.

Patented July 7, 1914.

Application filed January 12, 1913. Serial No. 741,673.

To all whom it may concern:

Be it known that I, WILLIAM B. TURNER, a citizen of the United States, residing in Wilmington, in the county of Newcastle, 5 State of Delaware, have invented a new and useful Leather-Finishing Machine, of which the following is a specification.

Heretofore in machines of the prior art, it has been customary to employ in the finishing operation of leather a glazing machine, and in some instances to thereafter subject the leather to the operation of an ironing machine, the foregoing operations or finishing steps requiring a considerable expenditure of time and necessitating the employment of a plurality of machines and usually two sets of operators to attain results which are inferior to those which I obtain in my present novel construction of leather machine.

By my present invention I have provided novel means for glazing and ironing a piece of leather at one and the same operation and in one and the same machine, whereby I attain results far superior to any of the results heretofore attained, wherein a plurality of the machines heretofore referred to are employed, the leather finished in my present novel construction of machine possessing a smoother grain and in many instances a finer finish than it has heretofore been possible to obtain by any means heretofore known or employed in this art.

My invention is intended to be used primarily on glazed kid and on calf skins of various grades, although it will of course be understood by those skilled in this art that the machine is capable of a wide variety of other uses, and I do not therefore desire to be limited to any particular grade of leather or class of work to which the same may be applied.

With the above in view, my invention in its broad and generic scope consists of novel means for controlling the operation of glazing devices and independent finishing devices with respect to the skin being treated.

My invention further consists of a novel construction of head or parallel bars carrying the operating tools and adapted to be raised and lowered at suitable points during its longitudinal travel, so that the non-revolvle glass and the rotatable roll will contact with the leather to be treated at the

same instant of time and will raise out of contact with the leather at the same instant.

It further consists of a novel construction of a movable head carrying in its forward portion a rotatable roll of any suitable material having preferably a smooth surface, said head also carrying a non-revolvle glass coacting therewith, novel means being provided for affecting the simultaneous reciprocation of the roll and the glass and for also affecting the elevation and forward movement of said roll and glass, whereby the two latter descend upon and contact with the leather to be treated at the same instant.

My invention further consists in a novel construction and arrangement of a plurality of links or pendulums whereby I am enabled to attain a uniform and simultaneous actuation of the leather treating devices, and novel means for intermittently raising and lowering such links or pendulums.

It further consists of a novel construction of a smooth roll for glazing or ironing purposes.

In prior devices employed for ironing purposes it has been necessary to artificially heat the same while in my present mechanism the necessary heat is developed from the friction of the roll on the skins being ironed.

It further consists of novel means for causing the glazing means and the ironing means to travel in a straight line during the working stroke and to return the same in a curved line to the point where the working stroke begins.

It further consists of other novel features of construction, all as will be hereinafter fully set forth.

For the purpose of illustrating my invention, I have shown in the accompanying drawings a preferred embodiment which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 is a side elevation of a leather glazing machine embodying my invention.

Fig. 2 is an end elevation of certain of the parts seen in Fig. 1. Fig. 3 is a plan view of the machine. Fig. 4 is a side elevation of certain detached portions of the machine. 5 Fig. 5 is a side elevation of a supporting device for an agate or glass burnisher. Fig. 6 is a perspective view of a guide, and a block adapted to slide thereon. Fig. 7 is a front elevation of a portion of a roll employed and means for supporting the same. Fig. 8 is a front elevation of the parts seen in Fig. 5. Fig. 9 is a side elevation of certain of the parts seen in Fig. 7.

Similar numerals of reference indicate 15 corresponding parts in the figures.

Referring to the drawings:—The frame of the machine comprises side members 1 and 2 which are retained in proper position with respect to each other by braces 3, 4, 5 20 and 6. Journaled in the side member 2 is a driving shaft 7 provided with a tight and a loose pulley 8 and 9 respectively. The inner end of the shaft 7 has rigidly secured thereon an arm 10 in which is fitted one end of a 25 rod 11 firmly secured in said arm by a set screw 12 or equivalent fastening devices, so that this shaft is prevented from rotating in said arm. The opposite end of the rod 11 is fitted into an arm 13 and is firmly secured 30 thereto by a set screw 14 to prevent rotation of said rod 11 in the arm 13. The object in securing the rod 11 in the arms 10 and 13 is to cause a pulley 15 fast on said rod 11 to be carried around by said arms 10 and 13, 35 as an integral part thereof, so as to impart a rotary motion to a pulley 16 without varying the distance between it and the pulley 15 when the bars 17 and 18, in which said pulley 16 is journaled, are reciprocating. 40 The arm 13 is rigidly secured to a shaft 19, journaled in the member 1 of the frame of the machine, and this shaft 19 has fast thereon a cam 20, adapted to operate a lever 21 fulcrumed at 22, in the side member 1 of 45 the frame.

23 and 24 designate links one end of each of which is loosely mounted on the rod 11 while the opposite ends of said links are loosely fitted on a shaft 25 carried by the 50 bars 17 and 18 so that when the arms 10 and 13 are in operation they impart a reciprocating motion to said bars and their adjuncts. The bars 17 and 18 have pivoted thereto, as at 26 and 27, the lower ends of the levers 28 55 and 29 respectively. The upper extremity of the lever 28 is pivoted at 30 to a link 31, the end of which opposite its pivotal point 30 is loosely fitted on a stud shaft 32 that projects from a standard 33 carried by the 60 machine frame. The end of the link 29 opposite the pivotal point 27 has secured in it a shaft 34 adapted to slide up and down in guides 35 that depend from the cross piece 36 that connects the upper portions of the 65 standards 33 and 37. The standard 37 is

carried by the side member 1 and standard 33 in side member 2 of the frame. The lever 28 has pivoted thereto, as at 38, one end of a link 39 whose opposite end is pivoted to a stud or pindle 40, rigidly fixed in the frame 70 of the machine. The lever 29 has pivoted thereto as at 41, one end of a link 42 whose opposite end is pivoted at 43 to a block 44 so that the rising and falling motions of said block 44 may be transmitted to the 75 link 42, and its adjuncts. Projecting from the standard 37 is a stud shaft 45, on which is pivoted one end of a link 46 whose opposite end is pivoted to the shaft 29 and is adapted to move in unison with the link 31 80 in order to properly actuate the lever 28. The lever 29 has pivoted thereto, as at 47, in Fig. 2, one end of a link 48 whose opposite end is pivoted at 49 to a block 50 so as to move up and down in unison with said 85 block 50 and operate the lever 29 and certain of its adjuncts. The block 44 has pivoted thereto as at 51, in Fig. 1, one end of a sleeve 52 that is screw threaded to receive one end of a rod 52^a, whose opposite end is 90 also screw threaded to engage a sleeve 53 pivoted at 54 to an arm 55, the latter being secured to a shaft 56 journaled in the frame 95 of the machine.

The shaft 56 has secured thereto an arm 57 to which is pivoted as at 58, a sleeve 59 that is screw threaded to receive one end of a rod 60 whose opposite end is also screw threaded to engage a sleeve 61 pivoted at 62, see Fig. 6, to the blocks 50, so that when 100 said rods 52^a and 60 move up and down by reason of the rocking of the arms 55 and 57, such up and down motions are transmitted to the blocks 44 and 50 and their adjuncts. The shaft 56 has secured thereon 105 an arm 62, see more particularly Fig. 1, to which is pivoted a sleeve 63 screw threaded to receive one end of a rod 64 whose opposite end is screw threaded to engage a sleeve 65 that is pivoted at 66 to the lever 21. The 110 screw threads on the rods 52^a, 60 and 64 are preferably right and left hand threads for the purpose of adjustment of said rods and their adjuncts. Pivoted in the upper portion of the lever 21 is a roller 67 that is 115 located in the cam groove in the arm 20 so as to impart a rocking motion to said lever 21.

As will be seen in Figs. 1 and 3, a belt 69 passes partly around the pulley 15 and partly around the pulley 16 so that a rotary 120 motion may be imparted to the latter from the pulley 15.

The shaft 25 has fast thereon a pulley 70 partly around which passes a belt 71 that also passes partly around a pulley 72 fast 125 on a shaft 73 carried by the bars 17 and 18. The shaft 73 has fast thereon a gear wheel 74 that meshes with a gear wheel 75 fast on a shaft 76 journaled in the bars 17 and 18. The shaft 76 has fast thereon a 130

5 pulley 77 partly around which passes a belt 78, said belt passing also partly around a pulley 79 fast on a shaft 80 journaled in plates 81 guided in the bars 17 and 18, as best seen in Fig. 7, so that a finishing or ironing roll 82, fast on the shaft 80 may move up and down with the plates 81 according to the varying thickness of a skin undergoing the process of glazing. The plates 10 81 are each formed with a slot 83, as seen in Figs. 1, 7 and 9, and through each of which passes a bolt 84 to properly guide said plates in their up and down movements. The plates 81 are provided with ears 85 15 adapted to receive the lower extremities of screw threaded rods 86, provided with nuts 87 and 88 so as to properly adjust the position of the roll 82 with respect to a skin to be glazed, and furthermore to adjust the 20 pressure of said ironing or finishing roll 82 upon said skin, it being noted that a spring 89 encircles each rod 86 and is interposed between the nuts 88 and a brace bar 90.

The bars 17 and 18 have secured thereto a 25 brace bar 91 through which passes the screw threaded rods 92 provided with nuts 93 and 94, see more particularly Fig. 8, so that the position of the glazing member 95, of agate, glass or other suitable material, as 30 well as the pressure of such glazing member upon a skin may be adjusted as desired. A spring 96 encircles each rod 92 and is placed between the nuts 94 and the brace bar 91. The lower extremity of each rod 92 35 is pivoted at 97 to a jaw 98 which with a jaw 99 is adapted to firmly clamp the glazing member 95 between them so as to cause said member 95 to follow the movements of the bars 17 and 18.

40 Interposed between the member 95 and the clamping jaws 98 and 99 is a cushion 100 of soft material to prevent injury to the glazing member 95. The jaw 99 is provided with adjusting nuts 101 and 102 45 adapted to regulate the pressure of said jaws 98 and 99 against the glazing member 95. The bars 17 and 18 are each provided with studs 103 that act as a guide for the stem 104 of the jaw 98 in order to prevent longitudinal movement of said stem. The jaw 98 has pivoted thereto, as at 105, one end of tension bars 106 whose opposite ends are connected at 107 to the bars 17 and 18. Said bars prevent lateral movement of said jaw, 50 while it is free to rise against the springs 96.

It will be seen on referring to Figs. 3 and 8 that the jaw 98 is provided with two tension bars 106.

It will be best seen from Figs. 1 and 3, 60 that a table or work support 108 is fitted in a framework 109 and is provided with inclined faces 110 and 111 that rest upon similar inclined faces 112 and 113 on a sliding member 114 guided in the frame-work 109. The sliding member 114 is in screw

threaded engagement with a rod 115 swiveled in said frame-work 109 and provided with a handle 116 whereby said rod 115 may be rotated so as to cause the member 114 to move to and fro and consequently raise, or 70 lower the table 108. The table 108 is provided with a strip of metal or other desired material 117, upon which is placed a cover of leather or its equivalent 118 upon which a skin to be glazed is placed. In the present 75 instance the outer extremity 119 of the layer or cover 118 is secured to the table 108, while its opposite end is provided with hooks 120 in screw threaded engagement with the nuts 121 whereby said cover 118 80 may be tightened under a desired tension upon the table 108.

The operation of my novel leather finishing machine is as follows: Before beginning the detailed description of the operation, attention is directed to the fact that in my present invention, I employ glazing means and ironing or finishing means located posterior thereto, in conjunction with mechanism for causing such means to act on the 90 leather during its travel in one direction, and for simultaneously elevating said means or bringing them out of contact with the leather so that on the return travel they will not engage with the leather which is 95 being treated. The pulley 8, driven by any desired source of power, transmits motion to the shaft 7 and through the arm 10, rod 11, arm 13, and shaft 19 imparts motion to the cam 20 fast on the shaft 19. The turning of the arms 10 and 13 about 7 and 19 as an axis imparts a reciprocating motion to the bars 17 and 18, through the links 23 and 24, it being apparent that the pulleys, gear wheels, etc., carried by said bars move 100 in unison therewith. When the bars 17 and 18 are in the position seen in Fig. 1, the glass or agate 82 and roll 95 are in their extreme right hand position and press upon a skin to be glazed upon the table 108. The 105 arms 10 and 13 in turning from the position seen in Fig. 1 into that seen in Fig. 3 bring the bars 17 and 18, and consequently the glazing means 82 and finishing roll 95 into their extreme left hand position, it being 110 understood that during the travel of the glazing means 82 and roll 95 in the direction just stated, the two latter bear against a skin placed upon the table 108 so as to glaze and iron said skin. It is apparent 115 that since the pulley 15 is fast upon the rod 11 it will impart a rotary motion to the pulley 16, through the belt 69, when the arms 10 and 13 and pulley 15 are turning in the direction indicated by the arrow *b* in Fig. 1, and around the shaft 7 as an axis. The 120 rotary motion of the pulley 16 is transmitted to the pulley 70, through the shaft 25; and consequently imparts motion to the pulley 72, shaft 73, and gear wheel 74 through the 125 130

belt 71. The gear wheel 74 transmits motion to the gear wheel 75 causing the shaft 76 and pulley 77 fast thereon to turn in a direction opposite to that of the arms 10 and 13, or in the direction indicated by the arrow *c* in the right hand extremity of Fig. 1, it being observed that motion is imparted to the pulley 79 from the pulley 77 through the belt 78.

Referring now to Fig. 1, it will be observed that the lever 21 remains stationary during the travel of the glass 82 and roll 95 from right to left by reason of the roller 67, carried by said lever 21, occupying a position within the dwell portion *d* in the cam groove 68. When the glass 82 and roll 95 have completed their movement from right to left, and in contact with a skin to be glazed, the bars 17 and 18 and the part carried thereby start to move from left to right and simultaneously with this movement, the dwell portion *e* in the cam groove 68 is brought in contact with the roller 67 as will be understood from Fig. 4, whereupon the lever 21 is turned upon its fulcrum 22 and is brought into the position seen in dotted lines in Fig. 1, whereupon a partial rotation is imparted to the shaft 56 causing the arms 62 and 55 to move into the positions seen in dotted lines. This change in the position of the arm 55, and likewise of the arm 57 seen in Fig. 2, causes a downward movement of the rods 52^a and 60 thereby lowering the blocks 44 and 50 to which they are connected. When the blocks 44 and 50 are in their lowermost positions the shaft 34 is moved from its position seen in full lines in Fig. 1 into that seen in dotted lines in said figure. This downward movement of the shaft 34 brings the levers 28 and 29 into the positions seen in dotted lines, whereupon the inner ends of the bars 17 and 18 are lowered while their outer ends are elevated, thereby removing the glass 95 and roll 82 from contact with a skin undergoing treatment. The glass 95 and roll 82 remain in their elevated positions during the travel of the bars 17 and 18 from left to right, Fig. 1, due to the dwell *e* in the cam groove 68. When the bars 17 and 18 have completed their movement in the direction just stated, the dwell *d* in the cam groove 68 is again brought in contact with the roller 67 thereby rocking the lever 21 and causing the rod 64 to move the shaft 52 and thus elevate the rods 52^a and 60 and consequently the shaft 34 through the mechanism hereinbefore described. When the shaft 34 is in its elevated position it returns the levers 28 and 29 to the positions seen in full lines whereupon the glass 95 and roll 82 are again brought into contact with a skin to be glazed and the operation herein described is repeated until the process of glazing a skin is completed.

Attention is directed to the fact that the links 39 have a fixed fulcrum at 40 which causes the center of the pendulums 28 to travel in a rectilinear path in their movement in both directions. The links 42 have a movable fulcrum, the movement of which causes the pendulums 29 to guide the bars 17 and 18 and cause the glass 95 and the roll 82 to travel in a straight line during the working stroke and return the same in a curved line to the point where the working stroke begins.

The operator moves the skin being glazed over the table 108, in the usual manner, so as to present all parts thereof to the members 82 and 95. As hereinbefore stated, the glazing glass 95 is firmly clamped between the jaws 98 and 99 to prevent the same from rotating under normal conditions. The glass 95 and roll 82 are yieldingly supported so that during the process of glazing and finishing, they are permitted to independently move up and down to compensate for varying thickness of a skin owing to the provision of the springs 89 and 96. The space between the glass 95 and roll 82 relatively to the table 108 and likewise the pressure of these upon a skin to be treated, may be adjusted by turning the nuts 87, 88, 93, and 94 on their respective rods 86 and 92 either to the right or to the left according to requirements. The space between the glass 95 and roll 82, relatively to the table 108, may also be adjusted by turning the crank handle 116 so as to rotate the screw threaded rod 115 either to the right or to the left in order to cause the sliding member 114 to move inwardly or outwardly and by reason of the inclined faces 110, 111, 112, and 113 raise or lower the table 108.

Attention is directed to the fact that both the glazing member 95 and the ironing member 82 are simultaneously brought into contact with the leather to be treated at the beginning of the operative stroke, and are simultaneously moved out of engagement with the leather when such operative stroke is completed.

Attention is also directed to the fact that the ironing or finishing roll is yieldingly mounted at a point posterior to the glazing member 95, and also that the glazing member 95 is yieldingly mounted so that either the glazing member or the ironing roll is permitted to have an independent vertical travel in accordance with the variation in thickness of the leather which is being treated.

It will also be seen that relative adjustment of the leather treating devices and the work support is provided either by adjusting the leather treating devices themselves or by manually adjusting the height of the leather support.

Attention is also directed to the novel

manner of imparting a reciprocating movement to the glazing and finishing means, and the novel means provided for causing the revolution of the ironing or finishing means 5 during its reciprocation.

In so far as I am aware, I am the first in the art to devise a leather finishing machine, wherein a continuously revolving ironing member is mounted posterior to the glazing member, and means for causing the same to simultaneously contact with the leather during their travel in one direction, so that the ironing means treat the surface of the leather which has just been acted on by the glazing 10 devices, and it is understood that my claims to such features are to be construed with corresponding scope.

It will be further apparent that the entire operation of the machine is automatic, so 20 that the only attention required by the operator is to shift the leather being treated, so that the entire surface will be acted upon in the manner herein described.

The smooth roll may be located in practice, either anterior or posterior to the glazing means, but for purposes of illustration I have preferred to show the same as being mounted posterior to the glazing means, since such arrangement has been found in 30 practice to give very marked and advantageous results, although it will of course be understood that I do not desire to be limited to the arrangement shown for the purpose of illustrating one manner of carrying out my 35 invention in practice.

It will now be apparent that I have devised a novel and useful construction of a leather treating machine, which embodies the features of advantage enumerated as 40 desirable in the statement of the invention and the above description, and while I have in the present instance, shown and described a preferred embodiment thereof which has been found in practice to give satisfactory 45 and reliable results, it is to be understood that the same is susceptible of modification in various particulars without departing from the spirit or scope of the invention or sacrificing any of its advantages.

50 Having thus described my invention, what I claim as new and desire to secure by Letters Patent, is:—

1. In a leather finishing machine, glazing means, ironing means, and devices for causing 55 said means to reciprocate and during their travel in one direction engage with the leather being treated.

2. In a leather finishing machine, glazing means yieldingly mounted, ironing means 60 yieldingly mounted posterior thereto, and devices for causing said means to travel over the leather being treated and simultaneously contact therewith.

3. In a leather finishing machine, a glass, 65 a smooth roll mounted posterior thereto,

means for revolving said roll, and devices for causing said glass and revolving roll to travel over the leather being treated.

4. In a leather finishing machine, a work support, glazing means movably mounted thereabove, ironing means rotatably mounted above said work support, means for revolving said ironing means, devices for relatively adjusting said work support with respect to said glazing means and said ironing means, and devices for causing said glazing means and ironing means to travel over the surface of the leather on said work support. 70

5. In a leather finishing machine, a work support, a movable carrier, a glazing member mounted therein, an ironing member mounted in said carrier posterior to said glazing member, means to simultaneously reciprocate said members, and cam actuated devices controlled by said means to cause 80 said members to move into engagement with the leather at the beginning of a stroke and to move out of engagement with the leather at the end of such stroke.

6. In a leather finishing machine, glazing means, ironing means mounted posterior thereto, devices for causing said means to reciprocate and during their travel in one direction engage with the leather being treated, and means for independently adjusting the glazing means and the ironing means with respect to the leather. 90

7. In a leather finishing machine, a carrier, a glazing glass carried thereby, a smooth roll yieldingly carried thereby, 100 means for reciprocating said carrier and for continuously revolving said roll, and adjustable means for intermittently raising and lowering said carrier and thereby said glazing glass and smooth roll during 105 their reciprocations.

8. In a leather finishing machine, a non-revolving glass, a revoluble roll co-operating therewith, means to revolve said roll, and means for bringing said glass and roll into 110 contact with the leather to be finished, and reciprocating said glass and roll during such contact.

9. In a leather finishing machine, a stationary support for the leather, a smooth roll, a glass mounted in advance of said smooth roll, and means to simultaneously bring said smooth roll and glass into contact with the leather and reciprocate said roll and glass during such contact, and to 115 intermittently move said roll and glass out of contact with the leather.

10. In a leather finishing machine, a glass, a smooth roll, means for advancing said glass and roll and causing them to return 120 in a different path from that in which they were advanced and to engage with the leather during their travel in one direction.

11. In a leather finishing machine, a glass yieldingly mounted, a smooth roll yield- 130

ingly mounted, means to impart a simultaneous travel to said glass and roll to cause them to advance in a substantially rectilinear path in engagement with the leather and to disengage from the leather and return in a different path from that in which they were advanced.

12. In a leather finishing machine, a carrier, a bracket movable therein, rods carried by said bracket, a brace bar through which said rods pass, nuts engaging said rods above said brace bar, nuts on said rods below said brace bar, springs between said last named nuts and said brace bar, a smooth roll mounted in said bracket, means to continuously revolve said roll, a glass, means for actuating said glass, and means to reciprocate said carrier to cause said roll to engage, during its movement in one direction, with the leather being treated.

13. In a leather finishing machine, a carrier, a bracket yieldingly mounted therein, a shaft journaled in said bracket, a smooth roll carried by said shaft, a belt operatively connected with said shaft to continuously revolve the same, driving means for said belt, a glass means for actuating said glass, and means to reciprocate said carrier to cause said revolving roll to engage during its movement in one direction with the leather being treated.

14. In a leather finishing machine, a driving shaft, an arm fixed thereto, a rod fixed to said arm, a pulley fixedly mounted on said rod, a carrier operatively connected

with said rod to reciprocate therewith, a smooth roll mounted in said carrier, and a belt operatively connected with said pulley and with said smooth roll.

15. In a leather finishing machine, a driving shaft, an arm fixed thereto, a rod fixed to said arm, a pulley fixedly mounted on said rod, a carrier operatively connected with said rod to reciprocate therewith, a smooth roll mounted in said carrier, a glass mounted in said carrier, and a belt operatively connected with said pulley and with said smooth roll.

16. In a leather finishing machine, a driving shaft, an arm fixedly mounted thereon, a rod fixedly secured to said arm, a pulley fixed on said rod, a carrier pivotally connected with and reciprocated by said rod, a smooth roll mounted in said carrier and operatively connected with and continuously revolved by said pulley, leather treating devices mounted in said carrier, and mechanism to intermittently raise and lower said carrier.

17. In a leather finishing machine, a smooth roll, a glass, means to cause said smooth roll and said glass to travel during their working stroke in a straight line and during their return stroke in a curved line, and means to revolve said smooth roll during its working stroke.

WILLIAM B. TURNER.
